DESIGN FOR A DRESSER OR SIMILAR ARTICLE

Marshall C. Pumphrey, Los Angeles, Calif., assignor to Barker Bros. Incorporated, Los Angeles, Calif.

Application November 26, 1935, Serial No. 59,773

Term of patent 3½ years

To all whom it may concern:

Be it known, that I, Marshall C. Pumphrey, a citizen of the United States, residing at Los Angeles, county of Los Angeles, State of California, have invented a new, original, and ornamental Design for a Dresser or Similar Article, of which the following is a specification, reference being had to the accompanying drawing, forming part thereof. The figure is a perspective view of a dresser or similar article, showing my new design.

The end opposite to that shown in the drawing is identical with the end as shown. The rear side is entirely plain.

I claim:

The ornamental design for a dresser or similar article as shown and described.

MARSHALL C. PUMPHREY.
